MARGIN STENCIL FOR POLISHING
FINGERNAILS

Louis Florio, New York, N. Y.

Application February 7, 1940, Serial No. 317,643

6 Claims. (Cl. 132—73)

This invention relates to new and useful improvements in a stencil for polishing fingernails.

More specifically, the invention proposes the construction of a stencil for use in polishing fingernails, and more particularly, for maintaining the even outline of the moon at the base of the fingernail while applying the finger lacquer or polish.

A further object of this invention proposes to characterize the stencil by a flat tubular member having the front portion of its bottom wall cut away and which carries a stencil element having its front end projecting beyond the front end of the tubular member and which is adapted 15 to be engaged over the moon with its front end immediately adjacent the front edge of the moon.

Still further it is proposed to provide a fulcrum element at the central portion of the bottom wall 20 of said tubular member and which is adapted to engage one's finger adjacent the back edge of the nail in a manner to be used as a fulcrum about which the stencil may be pivoted for lifting the front end thereof to permit the work to 25 be viewed.

Still further the invention proposes the provision of an elastic band mounted on the front of the tubular member for engaging about one's finger to hold the stencil in position on the finger 30 with the front end of the stencil element aligned with the moon as previously described.

For further comprehension of the invention, and of the objects and advantages thereof, reference will be had to the following description 35 and accompanying drawing, and to the appended claims in which the various novel features of the invention are more particularly set forth.

In the accompanying drawing forming a material part of this disclosure:

40 Fig. 1 is a plan view of a hand having a stencil according to this invention applied to the index finger thereof.

Fig. 2 is a front elevational view of the stencil per se.

45 Fig. 3 is a side elevational view of the stencil.

Fig. 4 is a view similar to Fig. 3 illustrating the pivoted position of the stencil.

Fig. 5 is a longitudinal sectional view of the stencil.

50 The stencil for polishing fingernails, according to this invention, includes a flat tubular member 10 having a portion of its front wall 10^a cut away. This tubular member is preferably constructed of sheet metal or other similar material and has a portion 10^b thereof doubled upon

itself. This portion 10^b is separated from the main portion thereof by forming the tubular member with an inwardly extending cut 11 extending inwards from the bottom wall of the tubular member to a position adjacent the top 5 wall thereof. The top wall thereof remains uncut and acts as a hinge about which the portion 10^b is adapted to be bent.

A stencil element 12 is extended through the tubular member 10 and is adapted to be shifted 10 forwards and backwards and has a rearwardly projecting rear end 12^a forming a handle for the stencil. This stencil element is preferably constructed of rubber and is frictionally but slidably extended through the tubular member 10 15 so that the same may be shifted relative to the tubular member to have its front end 12^b project from the tubular member the desired amount.

The rear end 12^a which acts as a handle portion permits the entire stencil to be shifted either to the right or to the left for properly aligning the front end of the stencil element 12 with the moon at the base of the fingernail.

A fulcrum 13 is formed at the central portion 25 of the bottom wall of the tubular member 10 and projects downwards for engaging one's finger adjacent the back edge of the fingernail as shown in Fig. 3. This fulcrum 13 is formed by rolling the front portion of the bottom wall backwards as shown in Fig. 3 for forming a downwardly extending projection about which the stencil may be conveniently pivoted for lifting the front end of the stencil element as shown in Fig. 4 for permitting the front end of the stencil 30 element to be lifted from the face of the nail to determine whether or not the nail polish or lacquer is being properly applied.

A resilient band 14 is mounted on the front of the tubular member 10 for engaging about one's finger for holding the stencil element 12 in an aligned position with the moon. This resilient band is substantially circular and extends across the top face of the tubular member 10 between the front end thereof and the fulcrum 13. 45 This resilient band 14 engages in the space between the tubular member 10 and the portion 10^b thereof and a novel means is provided for releasably holding the same in position for permitting the elastic band to be inter-changed in the event 50 it becomes broken or loses its resiliency due to continued use. This means comprises a lug 15 formed on the front end of the portion 10^b of the tubular member 10 and which is bent around and engaged against the bottom face of the tubular 55

member 10 as shown in Fig. 5. This lug 15 acts as a hook for releasably connecting the front end of the portion 10^b to the front end of the tubular member proper. When the hook 15 is released 5 the resilient band 14 may be inter-changed when desired.

The stencil element 12 may also be used by pulling the same through the tubular member 10 as shown at 12', so that the rear end 12^a will be 10 used to cover the base of the nail at a longer distance from the fulcrum 13. This end 12^a will permit a different contour to be stencilled on the finger nail since the elevation or tilt of the stencil element 12 is different from that, when the front 15 end 12^b is being used.

The operation of this device is as follows:

To use the stencil, according to this invention, when applying lacquer to a finger nail, the stencil is engaged upon the finger to which the lacquer is 20 to be applied by passing the end of the finger through the resilient band 14. The stencil is then drawn into a proper position in which the front end 12^b of the stencil element 12 will be engaged over the moon at the base of the nail for covering 25 the same to prevent the polish from being applied to the moon and for causing the polish to be applied with a smooth outline adjacent the front edge of the moon.

While I have illustrated and described the preferred embodiment of my invention, it is to be understood that I do not limit myself to the precise constructions herein disclosed and the right is reserved to all changes and modifications coming within the scope of the invention as defined 35 in the appended claims.

Having thus described my invention, what I claim as new, and desire to secure by United States Letters Patent is:

1. A stencil for polishing fingernails, comprising 40 a flat tubular member having the front portion of its bottom wall cut away, a stencil element extending through said tubular member and adapted to be shifted forwards and rearwards and having a rearward projecting rear and forming 45 a handle, a fulcrum on the central part of the bottom wall of said tubular member and projecting downwards for engaging one's finger, and a resilient band mounted on the front of said tubular member for engaging about one's finger 50 for holding the front end of said stencil element on the fingernail.

2. A stencil for polishing fingernail, comprising 55 a flat tubular member having the front portion of its bottom wall cut away, a stencil element extending through said tubular member and adapted to be shifted forwards and rearwards and having a rearward projecting rear end forming a handle, a fulcrum on the central part of the bottom wall of said tubular member and projecting 60 downwards for engaging one's finger, and a resilient band mounted on the front of said tubular member for engaging about one's finger for holding the front end of said stencil element on the fingernail, said stencil element being formed 65 of rubber.

3. A stencil for polishing fingernails, comprising 70 a flat tubular member having the front portion of its bottom wall cut away, a stencil element

extending through said tubular member and adapted to be shifted forwards and rearwards and having a rearward projecting rear end forming a handle, a fulcrum on the central part of the bottom wall of said tubular member and projecting downwards for engaging one's finger, and a resilient band mounted on the front of said tubular member for engaging about one's finger for holding the front end of said stencil element on the fingernail, said stencil element being slidably extended through said tubular member but being of a thickness to frictionally engage the 10 walls of said tubular member to frictionally maintain the same in position.

4. A stencil for polishing fingernails, comprising 15 a flat tubular member having the front portion of its bottom wall cut away, a stencil element extending through said tubular member and adapted to be shifted forwards and rearwards and having a rearward projecting rear end forming a handle, a fulcrum on the central part of the bottom wall of said tubular member and projecting downwards for engaging one's finger, and a resilient band mounted on the front of said tubular member for engaging about one's finger for holding the front end of said stencil element on the fingernail, said fulcrum being formed by rolling the cut away bottom wall of said tubular member backwards.

5. A stencil for polishing fingernails, comprising 20 a flat tubular member having the front portion of its bottom wall cut away, a stencil element extending through said tubular member and adapted to be shifted forwards and rearwards and having a rearward projecting rear end forming a handle, a fulcrum on the central part of the bottom wall of said tubular member and projecting downwards for engaging one's finger, and a resilient band mounted on the front of said tubular member for engaging about one's finger for holding the front end of said stencil element on the fingernail, said fulcrum being formed by rolling the cut away bottom wall of said tubular member backwards.
